UNITED STATES PATENT OFFICE.

CHARLES WILLIAM BEISER, OF BROOKLYN, NEW YORK, ASSIGNOR TO AMERICAN
SOLDIER COMPANY, OF BROOKLYN, NEW YORK, A CORPORATION OF NEW
YORK.

DESIGN FOR A TOY SMALL-ARM.

Specification for Design.

Patented June 7, 1921.

58,057.

Application filed November 17, 1920. Serial No. 424,794. Term of patent 14 years.

To all whom it may concern:

Be it known that I, CHARLES W. BEISER, a citizen of the United States of America, residing at Brooklyn, in the county of Kings and State of New York, have invented a new, original, and ornamental Design for a Toy Small-Arm, of which the following is a specification, reference being had to the accompanying drawing, forming part

Figure 1 is an elevation of a toy small arm showing my new design. Fig. 2 is a top plan view thereof.

I claim:

The ornamental design for a toy small arm, as shown.

CHARLES WILLIAM BEISER.
